UNITED STATES PATENT OFFICE

ALBERT F. SPARKS, OF SPRINGFIELD, OHIO, ASSIGNOR TO THE JAMES LEFFEL & COMPANY, OF SPRINGFIELD, OHIO, A CORPORATION OF OHIO

HYDRAULIC TURBINE BEARING: COOLING MECHANISM

Application filed March 14, 1929. Serial No. 347,056.

My invention relates to the cooling of bearings and in particular to the cooling of remote bearings of hydraulic turbines.

It is a further object of my invention to provide automatic cooling of these bearings by delivering water thereto from the head waters and into the tail waters of the turbine installation.

It is the object of my invention to provide for circulation of water from the head waters through the bearing and thence to the draft tube.

It is an object of my invention to provide for the discharge of the water through the bearing from the head waters into the discharge pit.

It is an additional object to provide means of circulating lubricant to a bearing, and of circulating water through a casing containing the lubricant so that the lubricant being applied to the bearing will be properly cooled and in turn cool the bearing.

It is my object to provide for the circulation of water due to the induction action of the outgoing water upon the water line.

It is a further object to provide an arrangement so that water may be syphoned through the bearing.

Referring to the drawings:

30 Figure 1 is a side elevation of an installation in which the water circulation is from the head waters through the bearing to the tail waters.

Figure 2 is a diagrammatic view of the 35 same construction.

Figure 3 is a diagrammatic view of the lubrication of the water system, showing the piping therefor with respect to the bearing casing and the bearing.

40 Figure 4 is a detail section showing the arrangement of the lubrication, and cooling system pipes with respect to the turbine runner shaft and the bearing blocks.

Figure 5 is a detail top plan view of the 45 bearing casing.

Figure 6 is a section on the line 8—8 of Figure 7, showing the manifold top of the bearing casing.

Figure 7 is a top plan view of the casing 50 with the manifold cover removed.

Referring to the drawings in detail, 1 is a power house in which is located an electric generator 2, driven by the hydraulic turbine runner shaft 3. The turbine is designated 4 and is provided with an outlet draft tube 5, 55 which discharges into the discharge pit 6 out of which flows the tail water 7. 8 designates the head water which flows around the inlet siphon tube 9, through the gates into the turbine 4, and thence through the draft tube 5.

In Figures 1 and 2 I have shown a bearing casing generally designated 10, to which lubricant is delivered from the grease compressor 11 by the pipe 12, and from which grease is 65 returned by the pipe 13 to the grease receptacle 14, whence it can be seen as it discharges in order to determine the state of lubrication of the bearing.

In order to cool this grease and to thereby 70 cool the bearing and maintain proper lubricating conditions, I provide a cooling system to which water may be supplied in a variety of ways.

For instance, the water may be taken in 75 through the inlet line 15 from the head waters 8, delivered to the bearing casing 10 and removed by the outlet pipe 16, where it may discharge into the draft tube as at 17.

When the discharge is into the draft tube 80 the suction in the draft tube serves to draw the water through the water circulation system.

Turning to the casing 10 it will be noted that the casing is provided with a cover composed of the halves 20 and 21. Such halves comprise a water circulation manifold. This manifold is provided with a central aperture 22 in which rotates the runner shaft 3. Packings 23 are provided for sealing the engagement between the manifold top of the casing 10 and the runner shaft 3. The water enters through the inlet pipe 15 into the annular chamber 24, thence downwardly 85 through the depending pipe 25 which extends to a point near the bottom of the casing within a well 26. It is spaced from the bottom 27 of the well so that the water can pass down through the pipe 25 and up through 90 95 100

the well 26 into the outlet manifold passage-way 28 and thence out the exit pipe 16.

This well 26 with the inside pipe 25 is suspended into the lubricant in the casing 10 as will be more fully seen in Figure 7. I have illustrated four of these depending wells and supply pipes which are located in the lubricant adjacent the bearing blocks 29. These blocks are held in cages 30 and are adjustably positioned by the screws 31. Thus, the lubricant closely adjacent to the bearing blocks is cooled, the bearings are in turn cooled and the lubricant and bearings both maintained in a proper condition.

15 The lubricant is also caused to circulate over these well tubes and over the bearing blocks as hereinbefore described.

It will be understood that I desire to comprehend within my invention such modifications as may be necessary to adapt it to varying conditions and uses.

Having thus fully described my invention, what I claim is new and desire to secure by Letters Patent, is:

25 1. In combination in a hydraulic turbine of a rotating shaft, bearings therefor, a casing around said bearings and shaft containing lubricant, a distribution manifold cover on said casing, an inlet water pipe connected thereto, an outlet water pipe connected thereto and depending well members extending through the lubricant in said casing in communication with the outlet members and spaced depending inlet pipes in said well members connected to the inlet member, whereby water is circulated through the lubricant.

40 2. In combination in a hydraulic turbine of a rotating shaft, bearings therefor, a casing around said bearings and shaft containing lubricant, a distribution manifold cover on said casing, an inlet water pipe connected thereto, an outlet pipe connected thereto and depending well members extending through

45 the lubricant in said casing in communication with the outlet members and spaced depending inlet pipes in said well members connected to the inlet member, whereby water is circulated through the lubricant, said inlet member having its free end in the head waters flowing to the turbine and its outlet end of the outlet member in the outgoing water flowing from the turbine.

55 3. In a hydraulic turbine, a runner shaft, bearings therefor, a casing surrounding the bearings containing lubricant, a water distribution manifold forming the top of said casing, water circulation pipes depending therefrom into the lubricant, and inlet and exit pipes communicating with the water flowing through the turbine for delivering water through the casing, which water is induced in its flow by the movement of the water through the turbine.

60 4. In a hydraulic turbine, a runner shaft,

bearings therefor, a casing surrounding the bearings containing lubricant, a water distribution manifold forming the top of said casing, water circulation pipes depending therefrom into the lubricant, and inlet and exit pipes communicating with the water flowing through the turbine for delivering water through the casing, which water is induced in its flow by the movement of the water through the turbine, and means for circulating lubricant through said casing.

5. In a hydraulic turbine, a runner shaft, bearings therefor, a casing surrounding the bearings containing lubricant, a water distribution manifold forming the top of said casing, water circulation pipes depending therefrom into the lubricant, and inlet and exit pipes communicating with the water flowing through the turbine for delivering water through the casing, which water is induced in its flow by the movement of the water through the turbine, and means for circulating lubricant through said casing under pressure, and means of observing said circulation in order to determine the condition of the lubrication at a remote point from the point of causing the circulation.

6. In a hydraulic turbine, a runner shaft, bearings therefor, a casing around said bearings, a cover comprising water manifolds having superimposed inlet and outlet chambers, a pipe depending from the upper chamber open at its bottom to a point near the bottom of the casing, a second pipe spaced from the bottom and the sides of the first pipe having an open top with a closed bottom, said second pipe communicating with the lower water chamber, an inlet water pipe connected to the upper chamber at one end and the head waters associated with the turbine at the other end, an outlet pipe connected at one end to the lower water chamber and its free end located in the outgoing waters from the turbine.

7. In a hydraulic turbine, a runner shaft, bearings therefor, a casing around said bearings, a cover comprising water manifolds having superimposed inlet and outlet chambers, a pipe depending from the upper chamber open at its bottom to a point near the bottom of the casing, a second pipe spaced from the bottom and the sides of the first pipe having an open top with a closed bottom, said second pipe communicating with the lower water chamber, an inlet water pipe connected to the upper chamber at one end and the head waters associated with the turbine at the other end, an outlet pipe connected at one end to the lower water chamber and its free end located in the outgoing waters from the turbine, a casing being adapted to contain lubricant around said depending pipes, and means for circulating said lubricant therein over said pipes.

8. In a hydraulic turbine, a runner shaft,

bearings therefor, a casing around said bearings, a cover comprising water manifolds having superimposed inlet and outlet chambers, a pipe depending from the upper chamber open at its bottom to a point near the bottom of the casing, a second pipe spaced from the bottom and the sides of the first pipe having an open top with a closed bottom, said second pipe communicating with the lower water chamber, an inlet water pipe connected to the upper chamber at one end and the head waters associated with the turbine at the other end, an outlet pipe connected at one end to the lower water chamber and its free end located in the outgoing waters from the turbine, a casing being adapted to contain lubricant around said depending pipes, and means for circulating said lubricant therein over said pipes under pressure.

20 In testimony whereof I affix my signature.

ALBERT F. SPARKS.
